SELF ALIGHTING SIGNAL POST

Filed Sept. 15. 1927

UNITED STATES PATENT OFFICE

JOHN RANK AND HENRY W. RANK, OF MINNEAPOLIS, MINNESOTA

SELF-ARIGHTING SIGNAL POST

Application filed September 15, 1927. Serial No. 219,634.

Our present invention relates to traffic signals of the self-arighting signal post type and especially to that type of signal post disclosed and broadly claimed in our prior application Ser. No. 54,240 filed September 3, 1925. The present invention, while embodying the broad features of said prior application, involves other and improved features which simplify the construction of the post, increase its ability to withstand violent shocks and give the post a neater or better appearance.

In the accompanying drawings, which illustrate the invention, like characters indicate like parts throughout the several views.

Referring to the drawings:

Fig. 1 shows the improved signal post in elevation;

Fig. 2 is a vertical axial section taken on the line 2—2 of Fig. 1;

Fig. 3 is a horizontal section taken on the line 3—3 of Fig. 1;

Fig. 4 is a horizontal section taken on the line 4—4 of Fig. 1; and

Fig. 5 is an elevation showing the lamp cage removed from the signal post.

The invention is capable of modification but in the preferred form illustrated in the drawings the body of the signal post is formed by a heavy elastic tube or casing 6. This tubular casing is made of rubber, preferably reinforced with fabric much like the outer casing of a pneumatic tire, and is of such stiffness that it will maintain itself normally in a straight upright form. As preferably constructed, the interior of this tubular casing is cylindrical, while the outer surface thereof is slightly increased in thickness toward its lower end. At its lower end, the tubular casing is anchored to the road bed or pavement *y*, and advisably this is accomplished by a highly efficient form of anchoring device illustrated in the drawings, and which anchor comprises an anchoring

cylinder 7 and an annular anchoring ring 8. The cylinder 7 has outturned flanges preferably at its outer ends, and said cylinder is embedded solidly in the concrete body of the road bed. The anchoring ring 8 has a downturned annular flange into which the lower

end of the elastic tubular casing 6 is telescoped and rigidly secured by nut-equipped bolts 9 passed through the downturned flange of said ring, through the lower end of said casing and, as shown, also through metallic inner clips 10. The said parts 7, 8 and 10 will preferably be iron or steel. The downturned end of the anchoring ring 8 is detachably secured to the outturned upper flange of the cylindrical or tubular anchor 7 by suitable devices such as machine screws 11.

The upper portion of the elastic tubular casing 6 is stiffened and reinforced by a thin but very strong metallic lining 12 to which the rubber inner surface of said casing is permanently and very securely united by vulcanization. The lower end of the metallic reinforcing lining 12 terminates far enough above the road bed to give the lower flexible portion of the tubular casing sufficient flexibility and elasticity to permit the post to be turned down into a horizontal position against the road bed. This post is, of course, self-arighting; that is, the resiliency and elasticity in the lower part of the tubular body 6 is such that the post will be quickly thrown back to its upright position whenever it is released and will maintain its upright position unless struck by an automobile, truck or the like.

In its upper portion, a considerable distance above the lower end of the metallic lining 12, the post is provided with a plurality of light passages arranged for signaling purposes, and these light passages open through the metallic lining 12 and through the body of the casing. The number of these light passages may be varied but as shown the post is provided with four circumferentially spaced light passages 13, with four circumferentially spaced light passages 14, with four circumferentially spaced light passages 15, and with four circumferentially spaced light passages 16. These light passages may be closed by transparent sheets or panes 17 preferably rectangular pieces of celluloid that are sprung into engagement with sheets formed in the opposite edges of the respective light passages so that the said trans-

parent sheets are made readily removable and replaceable.

The upper portion of the signal post is equipped with electric light bulbs, the wires of which may be readily brought into the lamps through the tubular post and anchoring base. As an important feature of this invention, the electric bulbs 18 are directly applied to sockets 19 mounted on a skeleton cage 20 that loosely fits within and is readily removable from the upper portion of the tubular metallic lining 12. This lamp cage 20 has large openings in line with the light passages of the post so that projection of light for signalling purposes is not interfered with. To the upper end of the cage 20 is rigidly secured a metallic head 21 that forms a cap to the post, which cap is preferably but slightly exposed above the stiffened upper body portion of the elastic casing. As shown, this head or cap 21 is rigidly but detachably anchored to the upper end of the post by means of screws 22 passed through the upper end portions of the casing 6 and lining 12 and screwed into the sides of said cap, as best shown in Fig. 2. With this construction, as is evident, when the screws 22 are removed, the cap 21 with the skeleton cage may be freely withdrawn from the post or freely inserted into the post. This makes both assembling and repairs of the post an easy matter for all the lamps and sockets may be readily assembled on the cage while the cage is outside of the post. The lower end of the cage 20 preferably terminates far above the lower end of the reinforcing or post-stiffening lining 12. Said lining 12 stiffens all of that portion above the necessary flexible lower portion of the post which makes the upper portion of the post very strong and rigid while the elastic outer portion 6 of the post affords a cushion which minimizes the effect of jars due to contacts with the post. This post, as has been found in practice, will withstand the very severe jars produced by automobiles or trucks running over the post at comparatively high speed. Not only is the initial shock of the post minimized but all of the subsequent impacts produced by the car running over the post are cushioned and reduced to a minimum. In practice, the rubber body of the tubular post will usually be reinforced with fabric but in some instances this reinforcement may be omitted, and this is true especially in respect to the reinforced upper portion of the rubber body.

With the large number of light openings 13, 14, 15 and 16 illustrated in the drawings it may be assumed that the transparent panes 17 of said openings are respectively colored green, red, orange and white to indicate, respectively, go, stop, traffic change and caution. The light openings 16 afford what is usually designated as a pilot light which will

be used when the other and usually automatically controlled signals are out of action.

It is important to note that the metallic lining 12 not only reinforces the upper portion of the integral resilient tubular body but that the head or cap 21 is directly anchored to the upper portion of this metallic lining, thereby indirectly anchoring the lamp cage to the said lining, which latter is extended well down into the lower body portion of the resilient tubular body.

From what has been said it will be understood that the invention above described in detail is capable of various modifications within the scope of the claims hereof.

What we claim is:

1. A signal post comprising an anchoring base, a resilient integral tubular body anchored to said base at its lower end, a tubular metallic lining telescoped into the upper portion of said resilient tubular body but terminating above said base so as to permit the post to be turned into an approximately horizontal position, and a lamp-equipped cage telescoped within and detachably secured to said resilient tubular body and its metallic lining, said resilient tubular body, its lining and said cage having light-emitting passages for signal purposes.

2. The structure defined in claim 1 in which said metallic lining is vulcanized to the interior of said resilient tubular body so that said lining constitutes a permanent part of said tubular body.

3. The structure defined in claim 1 in which said metallic lining is extended to a point substantially midway between the lower portion of said cage and said anchoring base permitting said tubular body to bend only at its lower portion.

4. A signal post comprising an anchoring base, a resilient integral tubular body anchored to said base at its lower end, a tubular metallic lining telescoped into the upper portion of said resilient tubular body but terminating above said base so as to permit the post to be turned into an approximately horizontal position, a lamp-equipped cage telescoped within and detachably secured to said resilient tubular body and its metallic lining, said resilient tubular body, its lining and said cage having light-emitting passages for signal purposes, and a head rigidly secured to the upper end of said cage and having a portion telescoped onto the upper end of said metallic lining and detachably but rigidly secured to the upper portion of said resilient tubular body and its metallic lining.

In testimony whereof we affix our signatures.

JOHN RANK.
HENRY W. RANK.
